UNITED STATES PATENT OFFICE.

JACKSON L. KAIL, OF CHICAGO, ILLINOIS.

WINDOW.

1,112,623.

Specification of Letters Patent.

Patented Oct. 6, 1914.

Application filed March 31, 1913. Serial No. 757,767.

To all whom it may concern:

Be it known that I, JACKSON L. KAIL, a citizen of the United States, residing at Chicago, in the county of Cook and State of Illinois, have invented a certain new and useful Improvement in Windows, of which the following is a full, clear, concise, and exact description, reference being had to the accompanying drawings, forming a part of this specification.

This invention relates to an improved construction of window by which the window is made in two parts so mounted in a window frame that one part counter-balances the other, the parts being so connected that they may be swung upon supporting levers so as to secure any desired degree of opening between the window sash and the casing. The counter-balancing of the sashes is secured without the use of weights of any description outside of the sashes themselves, and furthermore, the sashes are so disposed in the window frame that when the window is closed the two sashes lie substantially in the same plane, thus presenting a continuous and practically unbroken surface to the weather, which adds much to the architectural effect of the structure.

I am aware that constructions have been employed in the past in which the two sashes are connected by levers so as to counter-balance each other, and I do not therefore, claim broadly as my invention this arrangement.

On the other hand my invention consists in improved structural features by which the results described are secured, as well as a construction facilitating the use of iron or steel in the window frame and sashes for the construction of fire-proof windows.

In carrying out my invention, the sashes and frame are so constructed that there are interlocking joints all around each sash, both with the window frame and the other sash, as a result of which weather-tight joints are secured. When the sashes are moved to their opened positions, they lie on the same side of the window frame, preferably the inside, thus differing radically from those prior art structures wherein the sashes lie on opposite sides of the window frame when the window is opened.

In one embodiment of my invention I provide means carried by the window frame for guiding the lower end of each of the sashes. The upper portion of the upper sash is

pivoted to a pair of levers, each of said levers being rigidly secured to a pinion supported by the window frame. Each of these first mentioned pinions meshes with another pinion, which has rigidly secured thereto a lever pivotally connected to the upper portion of the lower sash. The devices connecting the sashes are so conformed and disposed that as the upper portion of the lower sash is moved inwardly and upwardly, the upper portion of the upper sash is automatically moved inward and downward.

In another embodiment of my invention I provide means for connecting the window sashes whereby an operation of the sashes similar to the operation of the sashes of the first mentioned embodiments of my invention is accomplished without the use of meshing pinions. In this second embodiment of my invention the desired operation of the sashes is secured by providing a novel arrangement of levers connecting the two sashes.

These and other features of the window of my invention are illustrated in the accompanying drawings and set forth in detail in the following descriptions.

In the drawings: Figure 1 shows in inside elevation a window and frame constructed in accordance with my invention. Fig. 2 is a vertical sectional view taken through the parts shown in Fig. 1 along the line 2—2 of Fig. 1. Fig. 3 is a vertical sectional view taken through the parts shown in Fig. 1 along the line 3—3 thereof. Fig. 4 is a fragmentary sectional view taken on the line 4—4 of Fig. 3. Fig. 5 is a perspective view illustrating one of the pivoted guiding members for the lower sash. Fig. 6 is a fragmentary elevational view illustrating how the lower sash is secured to the pivoted guiding members. Fig. 7 is a vertical sectional view illustrating a modified form of window embodying my invention; and Fig. 8 is a view similar to Fig. 7 illustrating the sashes so disposed that they are supported by the pivoted guiding members which normally serve to guide the lower portion of the lower sash.

Similar reference numerals refer to similar parts throughout the several views.

At 9 I have illustrated a rectangular window frame constructed of channels, as shown. Secured to the upper channel of each frame is a transverse bar 10, to which is secured an angle 11, as shown, the flange

of the angle being turned toward the inside of the window frame. The side channels of the window frame are also provided with angles 12, which correspond to the angle 11 5 of the upper channel, these last mentioned angles being secured to bars 13, which correspond to the bar 10, which supports the angle 11. The angles 11 and 13 are adapted to overlap suitable flanges carried by the 10 window sashes, and so provide a weather tight joint.

Disposed within the window frame, are upper and lower sashes 14 and 15. When the sashes are in the positions shown in Fig. 15 1, the channels constituting the top and sides of the upper sash, overlap inturned flanges of the angles supported by the window frame. The lower flange of the upper sash overlaps the bar constituting the top 20 of the lower sash. The flanges of the angles constituting the sides of the lower sash overlap the angles 12, as shown, and the lower portion of the lower sash is conformed as most clearly illustrated in Fig. 5, to fit 25 over a bar 16, extending transversely of the bottom channel of the window frame. Thus weather tight joints are had throughout, when the sashes are in their closed positions.

Pivoted to the side channels of the window frame at either end of the bar 16, are guiding rods 17, each of which is provided at its free end with an aperture 18. Carried by the side channels of the window frame near the tops of said channels, are brackets 30 35 19. Disposed between each of the brackets 19 and its supporting channel, is a pair of meshing pinions indicated at 20 and 21, each of said pinions having one of its bearings in one of the brackets 19 and its other bearing 40 in its associated channel. Rigidly secured to each of the pinions 20 is a lever 22, which is also pivoted to the upper portion of the upper sash 14. Rigidly secured to each of the pinions 21 is a lever 23, which is 45 also pivoted to the end of a bar 24, carried by the lower window sash 15. The bars 24 are preferably secured to the lower window sashes by means of screws 25—25, as illustrated. As clearly illustrated in Figs. 2 50 and 4, the levers 22 are spaced somewhat from the window frame in order that the levers 22 and 23 may pass each other when the sashes are moved to their opened positions.

Carried by each of the vertical channels of the window frame, is a guiding strip 26, preferably secured in place by means of screws 27—27, as illustrated. Pins 28 carried by the lower end of the upper sash are 55 adapted to ride behind the guiding strip 26 and so prevent the lower end of the upper sash from swinging away from the window frame when the sashes are moved to their open positions.

As most clearly illustrated in Fig. 5, the

lower sash is provided with a pair of strips 28', to each of which is pivoted a locking block 29, as shown. These blocks are positioned and secured in position by means of screws 30, extending from the inside of the 70 lower window sash. The purpose of these locking blocks is to retain the lower sash in engagement with the guide bars 17. When the parts are in operative position, the guiding bars are placed in the positions shown in 75 Fig. 5, and the locking blocks are turned by turning screws upon which they are pivoted, until the oblique surfaces of the block engage the adjacent portions of the sash, and the locking portions of the block project 80 out over the strip 28' and engage the adjacent guiding bar 17. Continued turning of the screws 30 locks the locking blocks rigidly in position.

At 31 I have illustrated a locking lever 85 which serves to engage a plate 32, and so lock the sashes in their normal vertical positions, as clearly shown in Fig. 1. When the sashes are to be moved to their open positions, the locking lever 31 is disengaged 90 from the plate 32 and the upper portion of the lower sash grasped and pulled inwardly and upwardly. As the lower sash is moved inwardly and upwardly, the upper sash, by virtue of the lever connections above described, is moved inwardly and downwardly. It should be noted that the construction of 95 the window above set forth is such that a metal construction may be had throughout, and that a weather proof exterior is presented to the weather when the sashes are moved to their closed position and locked.

At 33 I have illustrated a handle which may be used for moving the lower sash to its normal closed position or for moving the 105 sashes to their opened positions after the upper portion of the lower sash has been moved inwardly an amount sufficient to bring the lever mechanism into play.

In Figs. 7 and 8 I have illustrated a modified form of window construction wherein no pinions are used. In this form of window, the upper portion of the upper sash illustrated at 40 is pivoted to levers 41, which are in turn pivoted to the window frame at 42. The levers 41 are provided with ears 43, of reduced cross-section, which are pivoted in the bifurcated ends of links 44, the other ends of which are pivoted to the short arms of levers 45, pivotally mounted upon studs 46, carried by the window frame. The long arms of the levers 45 are pivotally connected to the upper portions of the lower window sash, as illustrated. In 110 this form of construction, the means for holding the lower portion of the lower sash in sliding engagement with the pivoted guide bars, illustrated at 47, is somewhat 115 different than the means provided in connection with the form of window illustrated 120 125 130

in Figs. 1 to 6 inclusive. In this second form of window construction, the guide bars 47 are placed between blocks 48, and the side flanges of the lower window sash. Pivot 5 plates 49 carried by studs 50 on the inside of the lower sash, are then swung through apertures in the side flanges to lock the guide bars 47 in position. The result accomplished by the form of window illustrated in Figs. 7 and 8 is in all respects the same as the result accomplished by the form of window illustrated in Figs. 1 to 6 inclusive. In Fig. 8 I have shown the lower end of the upper sash supported by the guide bars 47, 10 the apertures in the free end thereof being slipped over the pins which normally retain the lower end of the upper sash in sliding engagement with the window frame. It might be said that the sashes of the window 15 construction illustrated in Figs. 1 to 6 inclusive may also be supported as are the sashes illustrated in Fig. 8.

While I have illustrated my invention in the particular embodiments herein shown 25 and described, I do not wish to be limited to these particular constructions, but desire to claim broadly any equivalents thereof which may suggest themselves to those skilled in the art.

What I claim and desire to secure by Letters Patent of the United States is:

1. In combination, a window frame, upper and lower sashes, corresponding ends of the sashes having sliding and pivotal engagement with the window frame and devices connecting the other ends of the sashes, whereby the upper sash is moved downward and the connected ends of the sashes are moved toward the same side of the window 40 frame when the lower sash is moved upward.

2. In combination, a window frame, upper and lower sashes, corresponding ends of the sashes having sliding and pivotal engagement with the window frame and lever 45 mechanism connecting the other ends of the sashes, whereby the upper sash is moved downward and the connected ends of the sashes moved toward the same side of the window frame when the lower sash is moved 50 upward.

3. In combination, a window frame, upper and lower sashes, the lower end of each of the sashes having sliding and pivotal engagement with the window frame, and lever 55 mechanism connecting the upper ends of the sashes, whereby the upper sash moves downward and the connected ends of the sashes move toward one and the same side of the window frame when the lower sash is moved 60 upward, the lower end of one of the sashes moving slightly out of a vertical line as it moves relatively to the window frame.

4. In combination, a window frame, a pair 65 of sashes normally disposed in substantially the same vertical plane, corresponding ends

of the sashes having sliding and pivotal engagement with the window frame, levers pivoted to the other ends of each of the sashes, each of said levers being rigidly secured to one of a pair of meshing pinions 70 substantially as described.

5. In combination, a window frame, a pair of sashes normally disposed in substantially the same vertical plane, corresponding ends of the sashes having sliding and pivotal engagement with the window frame, a pair of levers pivoted to the other end of each of the sashes, each lever of each pair being rigidly secured to a pinion meshing with the pinion 75 secured to the corresponding lever of the 80 other pair.

6. In combination, a window frame, upper and lower sashes disposed in said frame, a pair of meshing pinions supported by said window frame, suitable lever mechanism 85 connecting one end of each of said sashes with one of said pinions, and devices connecting the other end of each of the sashes with the frame whereby the said sashes are adapted to be swung into substantially parallel planes on the same side of the window frame.

7. In combination, a window frame, upper and lower sashes disposed in said frame, a pair of meshing pinions supported by said window frame, suitable lever mechanism 95 connecting one end of each of said sashes with one of said pinions, and devices connecting the other end of each of the sashes with the frame whereby the said sashes are adapted to be swung into substantially parallel planes on the same side of the window frame, the lower portion of the lowermost sash having yielding sliding connection with 100 the window frame.

8. In combination, a window frame, upper and lower sashes within the frame, a pair of pinions connected by suitable lever mechanism to the upper portions of the uppermost sash, meshing with pinions connected 110 by suitable lever mechanism to the upper portion of the lowermost sash, means carried by the frame for guiding the lower portion of the upper sash, while permitting it to pivot and a pair of bars pivoted at the lower end of the window frame having sliding engagement with the lower portion of the lower sash.

9. In combination, a window frame, a pair of sashes within the frame having sliding and pivotal engagement with the frame, and devices connecting the corresponding ends of the sashes whereby when one of the sashes is moved from closed position to one side of the window frame, the other sash is simultaneously moved from closed position to the same side of the window frame.

10. In combination, a window frame, a pair of sashes within the frame having sliding and pivotal engagement with the frame,

and devices connecting the corresponding ends of the sashes whereby when one of the sashes is moved from closed position to one side of the window frame, the other sash is 5 simultaneously moved from closed position to the same side of the window frame, together with means for maintaining the sashes in substantially parallel relation when

they are moved from their closed positions to one side of the window frame.

In witness whereof, I hereunto subscribe my name this 22 day of March, A. D., 1913.

JACKSON L. KAIL.
